US00D330276S

United States Patent [19]**Mitchum, Jr.****[11] Patent Number: Des. 330,276****[45] Date of Patent: ** Oct. 13, 1992**

- [54] **HEATING PAD FOR A FOOD SERVICE CART**
- [75] Inventor: **Leonard L. Mitchum, Jr., Huntsville, Ala.**
- [73] Assignee: **Aladdin Synergetics, Inc., Nashville, Tenn.**
- [**] Term: **14 Years**
- [21] Appl. No.: **394,181**
- [22] Filed: **Aug. 15, 1989**
- [52] U.S. Cl. **D34/27; D7/323; D7/362**
- [58] Field of Search **D34/20, 17, 21, 27; 219/386, 445, 395, 404; 220/23.6; 312/250; D7/323, 339, 362, 364, 365**
